UNITED STATES PATENT OFFICE.

SEBASTIAN L. CALVERT, OF AUGUSTA, KANSAS.

VACUUM FLUID-CIRCULATING SYSTEM.

1,257,805.

Specification of Letters Patent. Patented Feb. 26, 1918.

Application filed October 19, 1917. Serial No. 197,438.

To all whom it may concern:

Be it known that I, SEBASTIAN L. CALVERT, a citizen of the United States, residing at Augusta, in the county of Butler and State 5 of Kansas, have invented certain new and useful Improvements in Vacuum Fluid-Circulating Systems, of which the following is a specification.

This invention relates to vacuum fluid 10 circulating systems for fluid cooled internal combustion engines and it is the dominant object of the invention to provide a construction covered in my co-pending U. S. application bearing Serial No. 186,793, 15 whereby the cooling fluid will be caused to positively and quickly return to the supply tank or radiator, subsequently its circulation through the jacketed engine, thus allowing the same to be more quickly cooled for re- 20 introduction into the engine jacket.

Another and equally important object of the invention is to provide means for preventing any overflow of water into the engine cylinders by way of the air intaking 25 means of the air valve, thereby insuring proper functioning of the air valve at all times.

The foregoing together with additional 30 advantageous details and arrangement of parts of the preferred embodiment of my invention will be clear from the specific description hereinafter contained when read in connection with the accompanying drawings forming part thereof, wherein said embodiment of the invention is illustrated for 35 the purpose of facilitating a full understanding of the present improvements.

In the drawings:—

Figure 1 is an end elevation of the im- 40 proved system,

Fig. 2 is a vertical section through the vacuum tank, and,

Fig. 3 is a horizontal section there- 45 through.

Similar characters of reference refer to similar parts throughout the several views of the drawings.

Having more particular reference to the drawings, E represents the jacketed cylinder of a stationary internal combustion engine, the same having cooling fluid conveying conduits 1 and 2 engaged with the jackets thereof for an obvious purpose. A conduit 3 is connected to the conduit 2 by 50 means of a suitable elbow and extends into engagement with a fluid supply tank 4, it

being noted in this connection, that a check valve 5 is interposed in the said conduit 3, the purpose of which will be presently apparent. By so connecting the pipe 3 to the 60 fluid supply tank 4 it will be readily understood that means are provided for conducting the cooling fluid to the jacket of the engine cylinder. Connected with the upper portion of the conduit 1 by means of the 65 conventional form of T-connection is a conduit 6, the remaining end of which is engaged with the top of the fluid supply tank 4. A second T-connection 7 is interposed in the conduit 6 and has an upright release 70 pipe 8 engaged therewith, which pipe opens into the atmosphere.

A vacuum tank 9 is provided and has its lower end connected to the adjacent end of the conduit 1 while the upper end thereof 75 has a T-connection 10 formed thereon, one branch of which receives the adjacent end of a ring angularly arranged conduit 11, which conduit in turn, extends into engagement with a fitting 12 having an air inlet valve 80 13 arranged in one of its branches. The lower or remaining branch of the fitting 12 receives the upper end of a conduit 14 therein, the lower portion of which is arranged at substantially right angles thereto 85 and pass into engagement with the engine air valve C, which air valve is provided with the usual mixer m.

As shown in Fig. 2 the vacuum tank 9 is formed of complementary sections hav- 90 ing screw threaded flanges formed upon the adjacent portions thereof to facilitate assembling of the same. A guide 15 is arranged in the vacuum tank 9 and receives therethrough the rod 16 of a float 17, the 95 upper end of the said rod carrying a valve 17' thereon adapted to normally seat upon the properly fitted portion 18 of the upper branch of the T-connection 10. Guide arms 19 may be and preferably are provided and 100 slidably receive the upper end of the rod 16 therethrough, thereby insuring proper movement of the valve 17 with relation to its seat.

Interposed in the conduit 6 is a check valve 20, the same serving as means for preventing the contents of the supply tank 4 from being effected by the partial vacuum created at times in the tank 9.

In operation, upon the intake stroke of the piston working in the cylinder of the engine E a partial vacuum is established in the tank 9 thereby causing the cooling fluid

to be circulated through the jacketed portion of the engine cylinder and drawn into the tank 9. Upon completion of the intake stroke, the partial vacuum in the tank 9 is lessened, thereby permitting the cooling fluid to be discharged into the conduit 6 and from there into the supply tank 4. As the fluid level in the tank 9 raises it follows that the float 17 will be raised thereby unseating the valve 17' and permitting the partial vacuum to be instantly broken and the cooling fluid discharged into the pipe 6 through the check 20. Further, the fluid will be prevented from entering the pipe 11. Due to the provision of the release pipe 8 it will be understood that additional air will be introduced into the cooling fluid, thus effecting the quick return thereof to the supply tank.

Manifestly, the construction shown is capable of considerable modification and such modification as is within the scope of my claims, I consider within the spirit of my invention.

I claim:

1. In a vacuum fluid circulating system, the combination with the jacketed cylinder of an engine and air valve, of a fluid supply means, means for conducting the fluid from the supply to the jacketed cylinder, a vacuum tank communicating with the conducting means, other means for establishing com-

munication between the air intake valve and said vacuum tank, and a release valve interposed in a portion of the conducting means and opening into the atmosphere.

2. In a vacuum fluid circulating system, the combination with the jacketed cylinder of an engine, of a fluid supply tank, means for conducting the fluid from the supply tank to said cylinder, a vacuum tank communicating with the conducting means, the upper portion of said vacuum tank being open, a float valve in the tank engageable over the upper end thereof, and air conducting means communicating with said tank and said air valve.

3. In a vacuum fluid circulating system, the combination with the jacketed cylinder of an engine and the air intake valve therefor, of a fluid supply tank, means for conducting the fluid from said tank to the jacketed cylinder, a vacuum tank communicating with said conducting means, the upper end of the vacuum tank being open, a float valve in said tank for normally closing said open upper end, air conducting means communicating with said tank and said air valve, and a release pipe interposed in a portion of said fluid conducting means.

In testimony whereof, I affix my signature hereto.

SEBASTIAN L. CALVERT.
